[57] CLAIM

The ornamental design for a combined table and multiple seat unit, as shown.

DESCRIPTION

FIG. 1 is a perspective view of a combined table and multiple seat unit of the present invention.

FIG. 2 is a top plan view of the article shown in FIG. 1.
FIG. 3 is an enlarged side elevation of the article of FIG. 1 looking toward a corner of the triangular table top.

FIG. 4 is an enlarged side elevational view of the article of FIG. 1 looking toward an elongated side edge of the triangular table top.

FIG. 5 is a bottom plan view of the article of FIG. 1.

FIG. 1
